UNITED STATES PATENT OFFICE.

JESSE THOS. CAMPBELL, OF ELBRIDGE, TENNESSEE.

WRENCH.

1,310,056.

Specification of Letters Patent.

Patented July 15, 1919.

Application filed February 5, 1919. Serial No. 275,140.

To all whom it may concern:

Be it known that I, JESSE T. CAMPBELL, a citizen of the United States, residing at Elbridge, in the county of Obion and State 5 of Tennessee, have invented a new and useful Wrench, of which the following is a specification.

The device forming the subject matter of 10 this application is a wrench, and one object of the invention is to provide novel means whereby the movable jaw may be held in adjusted positions with respect to the fixed jaw.

Another object of the invention is to provide a novel spring means for retracting the 15 movable jaw and for swinging outwardly the grips or levers which serve to hold the movable jaw retracted.

It is within the province of the disclosure 20 to improve generally and to enhance the utility of devices of that type to which the invention appertains.

With the above and other objects in view, 25 which will appear as the description proceeds, the invention resides in the combination and arrangement of parts and in the details of construction hereinafter described and claimed, it being understood that, 30 within the scope of what is claimed, changes in the precise embodiment of the invention shown can be made without departing from the spirit of the invention.

In the accompanying drawings:—

Figure 1 shows in side elevation, a wrench 35 constructed in accordance with the invention; Fig. 2 is a longitudinal section wherein parts appear in elevation; Fig. 3 is an elevation wherein the wrench is viewed at right angles to the showing of Fig. 1; Fig. 4 is a 40 perspective showing a portion of the handle and parts wherewith the latch co-operates.

In carrying out the invention there is provided a handle, denoted generally by the numeral 1, the handle including a fixed jaw 2, 45 a butt 3 and side plates 4 connecting the fixed jaw with the butt, these parts preferably being formed integrally. Recesses 5 are fashioned in the edges of the side plates 4, the recesses 5 defining reduced portions 6 in the side plates, the reduced portions being connected immediately with the butt 3. In the side plates 4, elongated slots 24 are fashioned. Notches 23 are formed in the reduced portions 6 of the side plates 4 at one 55 side of the wrench. The jaw 2 has a longi-

tudinal guide way 7 with which communicates a side opening 8 serving to permit the exit of dirt from the guide way 7.

The numeral 9 designates a movable jaw co-operating with the fixed jaw 2 and carried by a shank 10, the shank 10 including a head 11 mounted to slide in the guide way 7, the head merging into a reduced stem 12 slidable longitudinally between the side plates 4 and of the same width as the reduced portions 6 of the side plates. On the edges of the stem 12, racks 22 are formed. There is a longitudinal opening 14 in the butt 3 between the parts 6 of the side plates 4, and this opening communicates with a transverse opening 15 in the butt, there being slots 16 in the outer edges of the butt, the slot communicating with the opening 15. Disregarding for the moment, the slots 16 and the opening 15, it will be noted that one end of a retractile 75 spring 17 extends into the opening 14 and is held by a securing element 18 mounted in the butt 3 and extended across the opening 15. The other end of the spring 17 is attached at 40 to the end of the stem 12 of the 80 movable jaw 9. The stem 12 carries a pin or operating member, the ends of which move in the slots 24 of the side plates 4, the pin being terminally provided with heads 26 located exteriorly of the side plates 4 and 85 extending beyond the longitudinal edges of the slots 24.

Levers 19 extend longitudinally of the wrench and operate between the side plates 4, the levers being united by means of pivot 90 elements 20 with the side plates, relatively near to the fixed jaw 2, the stem 12 being located between the levers. The levers include broadened grips 21 movable in the recesses 5, the grips being supplied with projections 27 adapted to co-operate with the racks 22. At their free ends, the grips 21 are supplied with reduced fingers 28 movable in the slots 16 of the butt 3 and adapted to engage the ends of a compression spring 29 located in the opening 15 of the butt 3. At this point it may be observed that the securing element 18 which retains one end of the spring 17 engages, as well, the intermediate portion of the spring 29, the securing element constituting, therefore, a retainer for both springs. The ends of a bail-shaped latch 30 are pivoted at 31 to the butt 3. The arms of the latch 30 extend diagonally across the parts 6 on the side plates 4, and the transverse 110

end piece 100 of the latch is adapted to move into the notches 23 when the latch is swung on its pivotal mounting 31, to engage, at the will of an operator, with one of the 5 racks 22 on the shank 12, thereby to hold the shank 10 and the jaw 9 against the action of the spring 17, even though the grips 21 may not have been swung toward each other to cause the projections 27 to engage 10 with the racks 22.

Let it be supposed that the latch 30 is out of engagement with the notch 23 and the particular rack 22 wherewith the latch is adapted to coöperate. The spring 29, co- 15 acting with the reduced fingers 28, swings the levers 19 outwardly on their pivot mountings 32, so that the projections 27 on the grips 21 do not engage with the racks 22 on the stem 12 of the movable jaw 9. 20 The movable jaw now is responsive to the action of the spring 17 and that spring tends to draw the movable jaw 9 toward the fixed jaw 2. The thumb of the operator may be placed on one of the heads 26, the pin 25 25 moving in the slot 24 and advancing the stem 12, thereby to regulate the space between the movable jaw 9 and the fixed jaw 2, the spring 17 being put under tension. When the grips 21 are seized in the hand 30 of the operator, the levers 19 are swung inwardly on their pivotal mountings 20, wher- upon the projections 27 coöperating with the racks 22, will hold the stem 12 against longitudinal sliding movement and main- 35 tain the movable jaw 9 in adjusted relation to the fixed jaw 2. As soon as the hold on the grips 21 is released, the spring 29 will react on the fingers 28 and swing the levers 19 outwardly so that the projections 40 27 no longer engage the racks 22. Then the spring 17 will retract the movable jaw 9 toward the fixed jaw 2.

The foregoing operation presupposes that the wrench is to be operated by hand. On 45 a heavy job, it may be desirable to operate the wrench by means of the foot of the mechanic. Then, perhaps, neither of the levers 19 will be swung inwardly, partic- 50 ularly if the foot of the operator happens to be placed against the butt 3. If the levers 19, are not swung inwardly, the projections 27 will not coöperate with the racks 22 to hold the jaw 9 in fixed relation with respect to the jaw 2, and under such circumstances, 55 the bail-shaped latch 30 exercises its function, the free end portion of the latch being swung to the right (Fig. 2) until the trans- 60 verse end piece 100 of the latch enters the notches 23 in the parts 6 of the side plate and coöperates with one of the racks 22. From the foregoing will be observed that the operator has within his command, a 65 means for holding the jaw 9 in proper relation to the jaw 2, even though the levers 19 may not have been swung toward each

other, to cause the projections 27 to coöperate with the racks 22.

Having thus described the invention, what is claimed is:—

1. A wrench comprising a handle having 70 a fixed jaw; a movable jaw coöperating with the fixed jaw and including a stem slidable in the handle; and levers disposed on opposite sides of the stem, the levers being pivoted at their outer ends to the handle and 75 having their inner ends free for swinging movement toward and away from the stem, the levers being exposed to be gripped simultaneously, the levers and the shank having interengaging elements, those of said ele- 80 ments which are on the levers being located between the ends of the levers.

2. A wrench comprising a handle having a fixed jaw; a movable jaw coöperating with the fixed jaw and including a stem slidable 85 in the handle; levers disposed on opposite sides of the stem, the levers being pivoted to the handle and being exposed to be gripped simultaneously, the levers and the stem having interengaging elements; and a 90 latch mounted movably on the handle and adapted to coöperate at the will of an operator with one of said elements on the stem.

3. A wrench comprising a handle having a fixed jaw; a movable jaw coöperating with 95 the fixed jaw and including a stem slidable in the handle; levers disposed on opposite sides of the stem, the levers being pivoted to the handle and being exposed to be gripped simultaneously, the levers and the 100 stem having interengaging elements; and spring means for swinging the levers outwardly, to disengage said elements.

4. A wrench comprising a handle having a fixed jaw; a movable jaw coöperating with 105 the fixed jaw and including a stem slidable in the handle; levers disposed on opposite sides of the stem, the levers being pivoted to the handle and being exposed to be gripped simultaneously, the levers and the stem hav- 110 ing interengaging elements; spring means assembled with the stem and with the handle for retracting the stem and the movable jaw; and a latch movably mounted on the handle, and under the control of an operator, the 115 latch operating with one of said elements on the stem.

5. A wrench comprising a handle having a fixed jaw and including a butt having 120 a slot; a movable jaw coöperating with the fixed jaw and including a stem slidable in the handle; a lever pivoted to the handle, the lever and the stem having interengaging elements, one end of the lever being mounted to move in the slot; and a spring 125 in the slot and coöperating with said end of the lever.

6. A wrench comprising a handle having a fixed jaw and a butt, the butt being pro- 130 vided with openings disposed at an angle

to each other; a compression spring in one opening; a retractile spring in the other opening; a securing element in the butt and engaging the inner ends of both springs; a 5 movable jaw coöperating with the fixed jaw and including a stem slidale in the handle, the stem being connected with the retractile spring; and a lever pivoted to the handle, the lever and the stem having interengaging

elements, and one end of the lever being 10 engaged by the compression spring.

In testimony that I claim the foregoing as my own, I have hereto affixed my signature in the presence of two witnesses.
